SWAB

Paul F. Deford, Pasadena, Calif., assignor to D4
Drug Company, Ltd., Pasadena, Calif., a cor-
poration of Idaho

Application July 21, 1933, Serial No. 681,532

1 Claim. (Cl. 128—269)

This invention relates to improvements in
swabs.

The general object of this invention is to pro-
vide an improved swab which is adapted for gen-
eral use.

Another object of the invention is to provide
an improved means for securing the absorbent
material to the stem of a swab.

A further object of the invention is to pro-
vide a swab wherein means is provided whereby
the stem will remain dry.

A still further object of the invention is to
provide a swab which includes absorbent mate-
rial permanently fastened to a stem whereby
safety may be insured in using the swab in treat-
ment of the nose, throat, ears, etc. since there is
no likelihood of the absorbent material becoming
loosened or detached.

Other objects and the advantages of this in-
vention will be apparent from the following de-
scription taken in connection with the accom-
panying drawing wherein:

Fig. 1 is a side elevation of a pair of my im-
proved swabs;

Fig. 2 is a side elevation of the swab stem;

Fig. 3 is an enlarged fragmentary side eleva-
tion of the stem after treatment;

Fig. 4 is a perspective view of the absorbent
material before being positioned on the stem;

Fig. 5 is an enlarged fragmentary side elevation
of one end of the swab shown in Fig. 1 partly in
section and showing the swab partly completed;

Fig. 6 is a view similar to Fig. 5 showing the
completed swab; and,

Fig. 7 is a view similar to Fig. 1 showing a single
ended swab.

Referring to the drawing by reference char-
acters I have indicated my improved swab gener-
ally at 10. As shown the swab 10 comprises a stem
12 having a swab head 13 formed of absorbent
material at each end. In this description, I refer
to the swab as being made with double swabbing
ends but it will be understood that the swab may
be made with a single swabbing end.

The stem 12 is made of wood or other suitable
material and is saturated to a desired depth with
a sterilizing material such as a two percent (2%)
solution of mercurochrome. The end portions of
the stem 12 are then dipped in a glue-like mate-
rial 14 such as a mixture of gumtragacanth, boric
acid and water which forms a shell-like portion
extending over the ends of the stem and there-
along a predetermined distance.

The swab head 13 is formed of a square of ab-
sorbent cotton or other desired material 15 as

shown in Fig. 4. After the material 14 is placed
on the stem one end of the stem is positioned
on the square of cotton 15 and the cotton is pref-
erably rolled upon the stem into a conical forma-
tion, as shown in Fig. 5. This glues the interior
of the swab head to the stem.

The free end of the swab head extends beyond
the adjacent end of the stem 12 and the inner
end of the swab head may extend inward on the
stem beyond the inner end of the material 14. 10
After the cone of cotton 15 has been positioned
on the stem 12 a glue-like material 16, such as a
mixture of orange gum shellac and pure grain
alcohol is positioned over the inner portion of the
swab head (see Fig. 6). The material 16 ex-
tends from the extreme inner end of the swab
head to a location which may be approximately
intermediate the length of the material 14. The
swab head 13 at the opposite end of the stem 12
is formed thereon in a similar manner. 20

The device 10 may be used as thus formed as a
double ended swab or the stem 12 may be severed
intermediate its length to form a single ended
swab as indicated at 17 in Fig. 7.

Furthermore, the material 15 may be rolled 25
upon the stem to form flat ended swabs as shown
in Fig. 1, or it may be rolled upon the stem to
form a round ended swab as indicated at 18 in
Fig. 7.

By saturating the stem 12 to a desired depth 30
with mercurochrome the surface capillary at-
traction of the stem is diminished. Further, the
interior and exterior cements act as a stop pre-
venting capillary attraction in the swab stick.

As a result the stem 12 will not absorb moisture 35
from the swab head and will not become soggy
and flex and the coating 16 constitutes a shield
which retains moisture in the material 15 and
prevents it running along the stem 12.

From the foregoing description it will be ap-
parent that I have invented an improved swab 40
wherein the absorbent material is permanently
attached to the stem and cannot pull off or be-
come displaced and that this swab is simple in
construction and highly efficient in use. 45

Having thus described my invention, I claim:

A swab including a stem having a swab head
at one end thereof, said stem being made of wood
and saturated to a desired depth with sterilizing
material, a coating of adhesive material over one 50
end of said stem, said swab head being formed
of a piece of absorbent material wound upon said
stem in conical formation, the outer end of said
absorbent material extending beyond the ad-
jacent end of said stem and the inner end of said 55

absorbent material extending inward along said stem and over and beyond the inner end of said adhesive material, and a second coating of adhesive material which is insoluble in oils and water solutions positioned over said absorbent material adjacent the inner end thereof and se-

cured thereto, said second adhesive material extending from the inner end of said absorbent material to a location spaced from and overlapping said first adhesive material.

PAUL F. DEFORD.
